CONTROL INSTRUMENT CONSOLE AND SEATING UNIT ADAPTED FOR TRUCK MOUNTING

Donald E. Erdley, Wayne R. Mitchell, and William R. Shaffer, all of Huntingdon, Pa., assignors to Wald Industries, Inc., Huntingdon, Pa., a corporation of Pennsylvania

Filed June 25, 1965, Ser. No. 85,904

Term of patent 14 years

(Cl. D14—3)

FIG. 1.

FIG. 2.

FIG. 3.

FIG. 4.

FIG. 5.

FIG. 1 is a front perspective view, as seen from the rear of a truck, of a control instrument console and seating unit adapted for truck mounting;

FIG. 2 is a top plan view of the control instrument console and seating unit adapted for truck mounting showing our new design;

FIG. 3 is a front elevational view of FIG. 2;

FIG. 4 is a rear elevational view of our new design as shown in FIG. 2;

FIG. 5 is a right side elevational view of our new design.

The broken line showing of part of a truck body in FIG. 1 is for illustrative purposes only.

The essential features of our design are shown in full lines in the drawings.

This is a continuation-in-part of design application Serial No. D.82,826, filed November 27, 1964, and now abandoned.

We claim:

The ornamental design for a control instrument console and seating unit adapted for truck mounting, as shown and described.
